UNITED STATES PATENT OFFICE.

EDWARD POOLE, OF HALIFAX, ENGLAND, ASSIGNOR TO JOSEPH WILD & CO., OF NEW YORK CITY.

DESIGN FOR A CARPET-PATTERN.

Specification forming part of Design No. 5,650, dated March 12, 1872.

Specification describing a new and original Design for Carpets, invented by EDWARD POOLE, of Halifax, in the county of York, England.

The photographic illustration fully represents my new design for a carpet, which consists of two larger square figures, A and B, and of a light and graceful arrangement, C, of scrolls, lines, and foliage between the same. The square A embraces a bouquet of flowers, and is ornamented by ornamental outline. The square B has its corners beveled and its sides notched in the middle and provided with the projecting dents, as shown.

I claim as my invention—

1. The design of the square figure A, as shown.
2. The design of the square figure B, as shown.
3. The design of the filling C, as shown.
4. The design for a carpet containing the figures A B and filling C, as shown.

EDWARD POOLE.
